UNITED STATES PATENT OFFICE.

DAVID NADEL, OF SPINDLERSHOF, GERMANY.

PATTERN MECHANISM FOR EMBROIDERING-MACHINES.

SPECIFICATION forming part of Letters Patent No. 714,817, dated December 2, 1902.

Application filed April 9, 1902. Serial No. 102,047. (No model.)

To all whom it may concern:

Be it known that I, DAVID NADEL, a subject of the Emperor of Germany, residing at Spindlershof, in the Kingdom of Prussia and Empire of Germany, have invented certain new and useful Improvements in Pattern Mechanism for Embroidering - Machines; and I do hereby declare the following to be a full, clear, and exact description of the invention, such as will enable others skilled in the art to which it appertains to make and use the same.

My invention relates to embroidering-machines, especially machines of the Bonnaz type, illustrated in United States Patent No. 83,910. It is more especially an addition to the invention disclosed in my patents of April 8, 1902, Nos. 697,269 and 697,270. Its object is to provide an attachment by which the automatic feed-control mechanism may at the will of the operator be put out of action and a hand-operated means substituted; and to this end it comprises, essentially, an adjustable device, such as a dumb-bell pinion, interposed between the hand mechanism and the power or automatic mechanism to receive and transmit the power from either.

In the accompanying drawings, Figure 1 is a bottom plan view of the essential elements and immediately adjunctive mechanism. Fig. 2 is a side elevation looking in the direction of the arrows of Fig. 1. Fig. 3 is a section on the dotted line of Fig. 2 and looking in the direction of the arrows of that figure; and Fig. 4 is a section on the dotted line of Fig. 3 looking in the direction of the arrows.

1 represents a driving-pulley; 2 and 3, driving-gears; 4, a shaft, and 5 a bracket in which the shaft is mounted. These are all familiar features in this class of machines. So, also, 40 the looper-controlling mechanism, comprising the bracket 6, the lever-arm 7, the rod 8, the worm 9, and the guide-bracket 10, is a familiar feature, being particularly shown and described in the cited patent to Bonnaz, No. 83,910, and being illustrated here in a merely incidental manner to assist in locating the other parts. The pattern-drum 11, with its complementary paths 12, the guide-arms 13, the rods 14 and 15, and the crank-arms 16 45 and 17 at an angle to each other, are also fully shown and described in my previously-cited patents. It is the function of these parts to

control the feed mechanism, the crank-arms imparting the power through the shaft 18 and gear-wheel 19 to the shaft 20 through an intermediate mechanism, a gear device, to be hereinafter described, the shaft 20 in turn through a gear-wheel 21 meshing with a gear-wheel 22, rotating a shaft 23, and through gears 24 and 25 in turn rotating a shaft which 50 imparts the requisite power to mechanism fully illustrated and described in my preceding cited patents to control the feed mechanism, not necessary to illustrate here, it being sufficient to say that the ultimate purpose is 55 to control the action of the shaft which bears the gear-wheel 25.

In the earlier art—as, for example, in the cited Bonnaz patent—it was customary to employ a hand mechanism for controlling the feed mechanism. Even with the automatic regulation, such as given by the mechanism of my preceding cited patents, it is sometimes desirable to employ the hand mechanism—as, for instance, where it is desired to place some 60 intricate pattern at a corner. To this end I have joined with the automatic mechanism—that is, the pattern-drum, with its complementary paths—the connection - rods, the crank-arms at an angle to each other, and the 65 power-transmitting mechanism, as described, the familiar hand mechanism comprising a crank-handle 26, a bracket 27, and a shaft 28, bearing a gear-wheel 29. The essence of my invention lies in the joining of the automatic 70 controlling devices with the hand devices and interposing a mechanism by which the power may at the will of the operator pass either 75 through the automatic mechanism or the hand mechanism to the shaft borne by the gear-wheel 25. In the illustration the intermediate 80 mechanism is a double or dumb-bell pinion 30, which plays upon a feather on the shaft 20, and a shifting-lever 31, pivoted to the frame or bed of the machine at 32 and having a locking-screw, to be used when desired, at 33. The gear-wheel 29 meshes with a gear-wheel 34 on the end of a shaft 35, which is journaled in a bracket 36, and bears at the other 85 end a gear-wheel 37. The gear-wheels of the 90 dumb-bell pinion may mesh in turn with the gear-wheel 19 on one side or the gear-wheel 37 on the other side. When the machine is 95 running in the usual manner, with the pat-

tern-drum, connection-rods, and crank-arms governing the feed mechanism, the shifting-lever may be locked. The gear-wheel 19 then engages the outer gear-wheel of the dumb-bell 5 pinion 30 and through the shaft 20 and the succeeding connection drives the shaft which carries the gear-wheel 25. When it is desired to use the hand mechanism at difficult turns or at will, the shifting-lever 31 is brought 10 into use and the dumb-bell pinion is shifted on the shaft 20, so that power applied by the operator to the handle 26 may, through the shaft 28, gear-wheel 34, shaft 35, and gear-wheel 37, drive the shaft 20 through the inner gear-wheel of the dumb-bell pinion 30. 15

Having fully described my invention, what I claim is—

1. A feed-controlling mechanism for embroidery and other machines comprising an 20 automatic mechanism for controlling the feed, an independent hand mechanism for performing the same function, and an intermediate

adjustable mechanism which may at the will of the operator be moved into engagement either with the automatic mechanism or with 25 the hand mechanism to receive and transmit the power from either of the governing mechanisms.

2. A feed-controlling mechanism for embroidery and other machines comprising an 30 automatic power mechanism including a shaft bearing a gear-wheel, a hand-power mechanism including a shaft bearing a gear-wheel, a shaft bearing a dumb-bell pinion adjustable thereon, and means for shifting the dumb-bell pinion into engagement with either the gear-wheel of the automatic mechanism or the gear-wheel of the hand mechanism. 35

In testimony whereof I affix my signature in presence of two witnesses.

D. NADEL.
